CLAIM

The ornamental design for a cord securing assembly, as shown and described.

DESCRIPTION

FIG. 1 is a perspective view of a first embodiment of a cord securing assembly showing my new design.

FIG. 2 is a left elevation view of the cord securing assembly of FIG. 1, the right elevation view is a mirror image.

FIG. 3 is a front elevation view of the cord securing assembly of FIG. 1.

FIG. 4 is a rear elevation view of the cord securing assembly of FIG. 1.

FIG. 5 is a top plan view of the cord securing assembly of FIG. 1.

FIG. 6 is a bottom plan view of the cord securing assembly of FIG. 1.

FIG. 7 is a perspective view of a second embodiment of a cord securing assembly showing my new design.

FIG. 8 is a left elevation view of the cord securing assembly of FIG. 7, the right elevation view is a mirror image.

FIG. 9 is a front elevation view of the cord securing assembly of FIG. 7.

FIG. 10 is a rear elevation view of the cord securing assembly of FIG. 7.

FIG. 11 is a top plan view of the cord securing assembly of FIG. 7.

FIG. 12 is a bottom plan view of the cord securing assembly of FIG. 7.

FIG. 13 is a perspective view of a third embodiment of a cord securing assembly showing my new design.

FIG. 14 is a left elevation view of the cord securing assembly of FIG. 13, the right elevation view is a mirror image.

FIG. 15 is a front elevation view of the cord securing assembly of FIG. 13.

FIG. 16 is a rear elevation view of the cord securing assembly of FIG. 13.

FIG. 17 is a top plan view of the cord securing assembly of FIG. 13; and,

FIG. 18 is a bottom plan view of the cord securing assembly of FIG. 13.

(Continued)

All evenly-spaced broken lines are for environmental purposes only and do not form part of the claimed design.

1 Claim, 9 Drawing Sheets
